UNITED STATES PATENT OFFICE.

DANIEL MCFARLAN MOORE, OF NEWARK, NEW JERSEY, ASSIGNOR TO GENERAL ELECTRIC COMPANY, A CORPORATION OF NEW YORK.

VACUUM-TUBE LIGHTING.

1,042,587.

Specification of Letters Patent.

Patented Oct. 29, 1912.

Application filed February 26, 1907. Serial No. 359,445.

To all whom it may concern:

Be it known that I, DANIEL MCFARLAN MOORE, a citizen of the United States, and a resident of Newark, in the county of Essex and State of New Jersey, with post-office address 52 Lawrence street, have invented certain new and useful Improvements in Vacuum-Tube Lighting, of which the following is a specification.

10 My invention relates to that system of electric lighting devised by me wherein the light emanates from a column of gas contained in a sealed glass tube made up of sections of tubing joined end to end to make 15 a continuous gas-tight tube extended from one point to another over the area to be illuminated as described in my prior Re-issue Patent No. 1,256,1, dated Nov. 20, 1906.

In building up a tube of this character, 20 the practice has heretofore been to fuse the sections of tubing together end to end by the use of a glass blower's lamp or fire which is applied to the abutted ends of the tube when in place for the purpose of making a 25 fused glass joint.

The object of my present invention is to facilitate the building up of the tube and to make it possible to dispense with the services of the glass blower.

30 I have discovered that in the practice of my invention when carried out by the use of automatic gas feeding devices as described in my prior Patent No. 820,364, dated May 8th, 1906, it is practicable to install and operate the system by the use of 35 mechanical joints between sections of tubing, by which I mean joints formed by mechanical devices or by the application of cements in contradistinction to joints formed 40 by fusing the ends of the glass tubes directly together.

45 My invention consists in the construction of joints and fixtures for electric lighting tubes as hereinafter described and more particularly specified in the claims.

In the accompanying drawings, Figure 1 shows in side elevation a portion of a compound tube mounted in fixtures and supported in accordance with my invention.

50 Fig. 2 is a longitudinal section through a preferred form of fixture and joint for the meeting ends of the tube sections. Fig. 3 is a cross section through the fixture and glass tube on the line A, B Fig. 2. Figs. 55 4, 5, 6 and 7 illustrate forms of aluminum

or other metal sleeve or tube which may be employed in making the mechanical joint. Figs. 8, 9, 10, 11, 12 and 13 show other forms of mechanical joint that may be used in practising my invention.

60

Referring to Fig. 1, four sections of glass tubing 1 are shown end to end, the same constituting the end portion of the continuous lighting tube, one terminal only of which is shown in the casing 2 as provided 65 with the usual electric terminal or electrode 3.

4 is the ceiling or other support from which depend the rods or hangers 5 terminating at their bottom in suitable fixtures 6, on or in which latter the abutting or meeting ends of the sections are located and are connected to one another by a suitable mechanical seal or joint air and gas tight instead of by fusing. The ends of the tubes 70 for one form of such joint are indicated by the dotted line 17. The ring or other support 6 which encircles the end of the tubes where they meet and which, by the assistance of the hanger 5, affords a support for 80 the same may be of greater or less length in the direction of the axis of the tube according to the nature of the joint or mechanical seal. Said ring if of metal may be fastened to a porcelain insulating block 85 7 by means of a screw 8, said block being itself sustained properly in the tubular hanger 5 as illustrated in Fig. 2. This particular construction of insulating support for the tube I claim in my prior application 90 for patent filed Feb. 26, 1907, Serial No. 359,446, Patent No. 1,028,092.

The ring, tube or sleeve 6 for the form of joint shown in Fig. 2 is preferably provided at its ends with the compression rings 95 9 of metal connected by a screw thread with the ends of the metal tube and adapted to force sealing washers 10 into firm engagement with the outer surface of the sections of tubing where they fit or engage with 100 said tubes and also to force them against the inner surfaces of the metal thereby forming air and gas-tight joints so that, the remaining or intermediate portions of the metal sleeve or cylinder being unbroken and 105 gas-tight, gas will be prevented from leaking into or out of the tube through the joint at the abutting ends of the tube sections. This washer 10 may be of vulcanized fiber and may fit into the tapering mouth of the 110

metal tube as shown so as to be wedged tightly therein by the action of the screw rings 9, or said washer might be of some more elastic material which would tend to 5 expand in the direction of the plane occupied by the ring on being subjected to pressure parallel to the axis of the ring. In order to still further insure a good mechanical seal, I may employ in addition a 10 tube of metal such as aluminum indicated at 11. Said tube 11 may be formed as a sleeve to fit tightly upon the outside of both tube sections or may be a bushing to fit tightly on the inside of said meeting tube sections 15 or may lie inside one section and outside the other, this latter being the form shown in Fig. 2. The other forms are shown in Figs. 4 and 6 and likewise in Fig. 5.

Preferably, I construct this tube of aluminum in such form that it shall be engaged by the abutting edges of the tube sections when forced together end to end and being itself continuous will thereby more effectually complete the seal. Preferably, the portion so engaged consists of a 20 compressible section of a tube indicated at 12.

As shown in Fig. 5, the tube of aluminum or other metal might be plain or as shown in Fig. 7 and another tube 11' might be 30 applied over the same.

Within the metal ring or tube 6 is a mass of cement indicated at 13 which may be filled into the same through an opening 14 after the parts already described have been 35 located within the part 6. This still further perfects the mechanical seal.

Instead of a compressible ring or gasket 10 at the ends of the metal fixture operating with the tube 6 as described to make a mechanical seal, I may employ, as indicated in 40 Fig. 8, some material like a metal alloy readily fusible and of such character that it will unite readily with the glass tubing. Said metal alloy preparatory to the formation 45 of the joint may be held within the ends of the metal tube or ring 6 by means of the flanged metal rings 16 applied over the ends of tube 6. The ends of the sections of tubing having been located as in close contact as 50 may be within the ring 6, a blow pipe may be applied to melt the alloy and establish the mechanical seal required.

Fig. 9 shows another form of mechanical seal which may be employed and which, as 55 before, is preferably located within and supported by the tubular support 6 carried by the hanger or arm 5. In this form, the abutting ends of the tube sections are provided with flanges which retain the rings 17 60 and prevent them from meeting under the action of the clamping screws 18 which pass through arms extending from said rings. On the application of pressure through the medium of the sections, the abutted ends of 65 the tubes are forced firmly together and

held, the mechanical joint thus formed being properly supported in the ring or tube 6. To assist in the formation of this joint, any substance such as grease, oil, cement or other known sealing material may be placed between the abutted surfaces and said abutted surfaces may be curved as shown to further aid in producing a good joint. 70

Instead of using clamping devices, I may form the mechanical seal in the manner 75 shown in Fig. 11 by grinding the ends of the sections and fitting them into one another, grease, gum, glue or similar substance being employed on the ground surfaces, if desired.

As shown in Fig. 10, the sealing alloy may be employed without the use of retaining flanged rings 16. 80

Another form of mechanical joint that may be conveniently used is illustrated in 85 Fig. 13 wherein I show the supporting ring 6 as provided with a lining of asbestos 19, while the mechanical joint is made simply by the application of any cement or glue painted over the meeting edges of the tubes. 90

Fig. 12 shows a mechanical joint wherein in a sealing tape or cloth 20 is cemented over the line of meeting of the tube sections after which an outer layer of glue or cement of any kind, indicated at 21, is applied to 95 complete the joint.

What I claim as my invention is:

1. In a fixture for sectional vacuum tube lamps, a supporting sleeve of metal adapted to sustain the abutted ends of the sections 100 of glass tubing in juxtaposition within it, means for making a seal at the tube joint within said sleeve, a supporting tube, an insulating block sustaining the sleeve, means for fastening the sleeve to the block and 105 means for fastening the block to the supporting tube.

2. A combined fixture and seal for vacuum tube lamps having sections of glass tubing arranged end to end, comprising a supporting 110 sleeve and hanger for sustaining the tube at the meeting of the sections, a sealing sleeve formed with a compressible off-set adapted to lie between the abutting edges of said sections and means on said sleeve for forcing 115 said sections together.

3. In a fixture for a vacuum tube lamp having sections of glass tubing arranged end to end, a sleeve surrounding and sustaining the junction of the tubes and of 120 larger internal diameter than the outer diameter of the tubes themselves, compression rings upon the ends of said sleeve, sealing washers engaged by said rings and located in the ends of the sleeves, cementing material filling the space between the sleeves and the tubes and a tube 11 applied over the tube at the joint between the tube sections and lying partially between their abutting ends as and for the purpose described. 125 130

4. In a fixture for vacuum tube lighting, the combination of a supporting tube, a block of insulation having a vertical countersink, a tube-supporting ring, a fastening screw for securing the ring to the lower side of the block and a clamping screw passing through the side of the supporting tube and into said block to clamp it in said tube.

Signed at New York in the county of New York and State of New York this 30th ¹⁰ day of January A. D. 1907.

DANIEL McFARLAN MOORE.
